UNITED STATES PATENT OFFICE

FRANK J. KELLEY, OF MILWAUKEE, WISCONSIN, ASSIGNOR TO PANTHER RUBBER MANUFACTURING COMPANY, OF STOUGHTON, MASSACHUSETTS, A CORPORATION OF MASSACHUSETTS

DESIGN FOR A SHOE HEEL

Application filed April 25, 1932. Serial No. 43,603. Term of patent 14 years.

To all whom it may concern:

Be it known that I, FRANK J. KELLEY, a citizen of the United States, residing at Milwaukee, county of Milwaukee, State of Wisconsin, have invented a new, original, and ornamental Design for a Shoe Heel, of which the following is a specification, reference being had to the accompanying drawing forming a part thereof.

In the drawing, Fig. 1 is a plan view of a shoe heel showing my new design; and Fig. 2 is a cross-section on line 2—2 of Fig. 1.

I claim:

The ornamental design for a shoe heel as shown.

FRANK J. KELLEY.
